UNITED STATES PATENT OFFICE.

URBANE J. EWING AND ADA F. EWING, OF WILKINSBURG, PENNSYLVANIA, AS
SIGNORS TO PITTSBURGH LAVATORY SUPPLY INC., OF PITTSBURGH, PENNSYLVANIA, A CORPORATION OF DELAWARE.

MOP HOLDER.

Application filed May 24, 1926. Serial No. 111,298.

This invention relates to mop holders and more especially to that type in which is provided a stationary member attached to a handle and a hinged or movable clamp 5 adapted to firmly and properly secure the mop to the stationary member.

The objects of the invention are:

First, to provide a mop holder of the character above indicated which is cheap 10 to manufacture and consists of a minimum number of parts and in which the parts comprising the elements to hold or firmly clamp the mop can be quickly adjusted and the unclamping and removal of the mop from 15 the holder can be easily effected with the least number of manual operations.

Second, to construct a mop holder in such a manner so that when the mop has been clamped to the holder and the mop holder 20 is in position to be used in wiping or mopping a plane surface either in a horizontal or vertical position only the soft texture of the mop is capable of coming in contact with the surface of the floor or other body to be 25 mopped, thereby preventing the abrasion of floor or scratching of the body surface due to the contact of metal forming the holder with said floor or body surface.

Third, to form a mop holder of such contour and cross section as will enable the holders to be easily packed for shipment in a minimum of space and at the same time prevent their shape or any of the adjustable parts from becoming distorted or injured 35 tending to make them inoperative after being unpacked for sale.

Fourth, other advantages of construction and relation of the parts will be apparent and understood from the detailed description 40 to be hereinafter disclosed.

The invention consists of structural characteristics and relative arrangement of elements which will be hereinafter more fully described and particularly pointed out in 45 the appended claims.

In the drawings, in which similar reference characters indicate the same parts in the four figures:

Figure 1 is a perspective view of the improved mop with parts broken away.

Figure 2 is an enlarged sectional view taken on line II-II of Figure 1.

Figure 3 is an enlarged sectional view taken on line III-III of Figure 2; and

Figure 4 is a top plan view on an enlarged scale of one end of the holder.

Referring to the drawings, 10 is an elongated rectangular base section provided with a plane bottom 11 having integrally formed in its outer edges a raised web or flange 12 arranged normal to the plane of the bottom 11 and forming a shallow recess or pocket 13, as clearly shown in Figure 1, and for purposes to be hereinafter explained.

A rod 14 disposed in substantially the same plane as the plane of the bottom 11 is rigidly attached or secured preferably to the outer side of the bottom 11, and in such a position or manner so that the longitudinal axis of said rod 14 is normal to the adjacent or longer sides of the base 11 as illustrated. Said rod 14 at its outer extremity is made hollow to receive the end of handle 15 as is customary in this class of devices and needs no further explanation.

16 is a dished clamping member comprising a bottom 17 having integrally formed thereon on its outer edges a raised web or flange 18 arranged normal to the plane of the bottom 17 forming a recess 181, and is of a smaller depth than the web or flange 12 of the base section 10, and of such shape and size as to fit or be seated in the shallow recess or pocket 13 of the base section 10 with a slight clearance between the outer sides of the flange 18 of the clamping member 16 and the inner sides of the flange or web 12 of the base section 10, as clearly shown in Figures 1 and 2, and the plane of the outer side of the bottom 17 of the clamping member 16 is below the plane of the top edges of the web or flange 12 of the base section 10 when said clamping section 16 is within the recess or pocket 13 of said base section 10 with the recesses 181 and 13 of said clamping member 16 and base section 10 facing each other, as illustrated in Figure 2.

The clamping member 16 is rigidly secured to one end of a slightly yielding spring link 19, while the other end of said link 19 is hinged or pivotally connected to the rod 14, and while I have shown this pivotal connection by means of a turned-up

section of metal 20, struck out from the rod 14 engaged by an eye 21 in the end of link 19, any other pivotal or hinged connection between said rod 14 and link 19 may be provided without in any way changing the operation of the present invention.

The flange or web 12 of the base section 10 nearest to the rod 14 and hinged end of the link 19 is partially removed at 22 to form a socket in which the link 19 can be inserted when the clamping member 16 is seated within the pocket or recess 13 of the base section 10, as shown.

23 is a clamping ring encircling the rod 14 and link 19 and is adapted to slide back and forth on said rod 14 and link 19 and when in the position shown in full lines in Figures 1 and 2, firmly and immovably holds the clamping member 16 within the recess 13 of the base section 10, and said clamping ring 23 is held in position by means of the spring action of the yielding link 19, as will be readily understood.

The manner of using the mop holder is as follows: The mop holder is placed in the position shown in Figure 1 and the clamping ring 23 is slid back beyond the hinged end or pivotal connection of the link 19, which permits the clamping member 16 to be elevated and entirely removed from the recess 13 of the base section 10. The mop M is then adjusted so that one of its ends or edges is seated in the recess 13 of the base section 10, and then the clamping member 16 is permitted to drop in said recess 13 and assume the position shown in Figure 1 and the clamping ring 23 is then slid up and forced against the spring action of the link 19 until it is firmly held thereby when the mop M will be securely wedged and clamped within the recesses 13 and 181 of the section 10 and dished clamping member 16, and the edges of the flange or web 12 biting into mop M within said pocket or recess 13 of the base section 10 and owing to the outer side of the bottom 17 of the clamping member 16 being removed from the top edges of the flanges or raised webs 12 of the base section (see Figure 2), said mop M will at all times prevent any metal parts of the mop holder from coming in contact with the floor or other body and scratch or injure the same while the mop holder is being moved back and forth over said floor or other body. This is a most important and advantageous feature of the present invention and will carry out safely such advantageous operations whether the mop handle is depressed or elevated, as will be clearly seen by reference to Figure 2.

Furthermore, when it is desired to remove the mop M from the holder, all that is necessary is to place the mop holder in the position indicated in Figure 2, slide back the clamping ring 23 to the position

shown in dotted lines, and said clamping member 16 will drop down into the position shown in dotted lines and quickly release the mop M without further manipulation on the part of the operator.

70

From the foregoing disclosure of the construction and arrangement of the improvement and mode of applying the same, it will be seen that all the objects and advantages recited in the statement of invention have been fully and efficiently carried out, and while I have shown and described my preferred form of the mop holder, many changes will readily suggest themselves without in any way departing from the salient features herein disclosed and embodied in the scope of the claims.

75

80

What is claimed is:—

1. A mop holder comprising a base section provided about its periphery with a raised web forming a shallow recess or pocket, a rod in substantially the same plane as the plane of the base section and attached thereto to one of the sides of the base section, a dished clamping member of less depth than the depth of the recess or pocket formed on the base section and adapted to fit with a slight clearance within the recess or pocket and below the top edges of the web of said base section and means for holding said dished clamping member within said recess or pocket of the base section with the recesses of said clamping member and base section facing each other.

90

2. A mop holder comprising a base section provided about its periphery with a raised web forming a shallow recess or pocket, a rod in substantially the same plane as the plane of the base section and attached thereto perpendicular to one of the sides of the base section, a dished clamping member pivotally connected to said rod and of less depth than the depth of the recess or pocket formed on the base section and adapted to fit with a slight clearance within the recess or pocket and below the top edges of the web of said base section and means encircling said rod and pivotal connection between said clamping member and rod for holding said dished clamping member within said recess or pocket of the base section with the recesses of said clamping member and base section facing each other.

100

105

110

115

3. A mop holder comprising an elongated rectangular narrow base section provided about its periphery with a raised web normal to the plane of said base section and forming a shallow rectangular recess or pocket, a rod in substantially the same plane as the plane of the base section and attached thereto normal to the elongated sides of the narrow base section, an elongated rectangular dished clamping member of less depth than the depth of the recess or pocket formed on the base section and adapted to fit with

120

125

130

a slight clearance within the recess or pocket and below the top edges of the web of said base section and means for holding said dished clamping member within said recess or pocket of the base section with the recesses of said clamping member and base section facing each other.

4. A mop holder comprising an elongated rectangular narrow base section provided about its periphery with a raised web normal to the plane of said base section and forming a shallow rectangular recess or pocket, a rod in substantially the same plane as the plane of the base section and attached thereto perpendicular to the long sides of the narrow base section, an elongated rectangular dished clamping member pivotally

connected to said rod and of less depth than the depth of the recess or pocket formed on the base section and adapted to fit with a slight clearance within the recess or pocket and below the top edges of the web of said base section and a ring loosely encircling said rod and pivotal connection between said clamping member and rod for holding said dished clamping member within said recess or pocket of the base section with the recesses of said clamping member and base section facing each other.

In testimony whereof we hereunto affix our signatures.

URBANE J. EWING.
ADA F. EWING.

CERTIFICATE OF CORRECTION.

Patent No. 1,630,418.

Granted May 31, 1927, to

URBANE J. EWING ET AL.

It is hereby certified that the assignee in the above numbered patent was erroneously described and specified as "Pittsburgh Lavatory Supply Inc., of Pittsburgh, Pa., a Corporation of Delaware", whereas said assignee should have been described and specified as "Pittsburgh Sanatory Supply Inc., of Pittsburgh, Pa., a Corporation of Delaware", as shown by the records of assignments in this office; and that the said Letters Patent should be read with this correction therein that the same may conform to the record of the case in the Patent Office.

Signed and sealed this 23rd day of April, A. D. 1929.

(Seal)

M. J. Moore,
Acting Commissioner of Patents.
